HOSE REEL

Filed Feb. 18, 1931

INVENTOR.
Abraham Ludwig

BY
Thomas J. Donnelly
ATTORNEY.

UNITED STATES PATENT OFFICE

ABRAHAM LUDWIG, OF DETROIT, MICHIGAN

HOSE REEL

Application filed February 18, 1931. Serial No. 516,665.

My invention relates to a new and useful improvement in a hose reel and has for its object the provision of a hose reel on which a hose may be wound while connected to a source of water supply.

It is another object of the invention to provide a hose reel whereby the attaching and detaching of the hose to and from the water supply pipe may be eliminated while at the same time the hose may be wound on a reel and kept in proper condition.

Another object of the invention is the provision of a hose reel on which a hose may be wound and which is so constructed that when the hose is unwound therefrom and the strain released from the hose a rewinding of the hose on the reel may be automatically effected.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a side elevational view of the invention.

Fig. 2 is a central, sectional view of the invention, with parts broken away.

Fig. 3 is a sectional view taken on line 3-3 of Fig. 2.

Fig. 4 is a transverse sectional view of a modified form of the invention.

Fig. 5 is a side elevational view of a modified form of the invention with a part broken away and a part shown in section.

In the construction shown in Fig. 1, I have illustrated the invention mounted beneath a floor 7 projecting downwardly from which are the spaced joists 8. Secured to and depending from the floor is a bracket or support 9 braced by the brace 10 and having an upwardly projecting plate 11 provided with a slot 12. A co-operating bracket 13 also is secured to and depends from the floor 7 and is braced by the brace 14. A projection 15 extends upwardly from the lower end of the bracket 13 in which is journaled, so as to rotate therein, a trunnion or neck 16 projecting

outwardly from one end of the block 17. This block 17 is secured by a pressed fit in the sleeve or tube 18. Positioned within the tube or cylinder 18 is a spring 19, one end of which is secured to the tube 18 and the other end of which is secured to the plug 20 which is rotatable relatively to the tube 18. A prong 21, which is flat faced, projects outwardly from one face of the plug 20 and engages in the slot 12 so that the spring 19 is wound and unwound as the tube 18 rotates in different directions. Fixedly mounted on the tube 18 is a drum or winding reel 22 on the periphery of which are the spaced axially extending cleats 22' which engage the hose 23 which is wound thereon. One end of the hose is connected to the pipe 24 which connects to the pipe 25 and through the pipe 26, elbow 27 and passage 28, to the pipe 29 which rotates with the neck 16. The pipe 29 is connected by the coupling 30 to the pipe 31 which is provided with the head 32 rotatably mounted in the housing 33. This housing is threaded onto the end of the water supply pipe 34. A packing block 35 is adapted to co-operate with the packing gland 37 and compress the packing 36 about the pipe 31 within the housing 33 to form a leakproof connection.

It is believed obvious that as the hose is unwound from the reel, the tube 18 may rotate and serve to wind the spring 19 and that when tension is released from the hose, the spring 19 will serve to again wind the hose thereon.

In Fig. 4, I have shown a slightly modified form of the invention in which the hose is projected through a passage 38 formed in the wall 39, the reel 22 and its co-operating parts being constructed as already described.

In Fig. 5 I have shown the device mounted on a base 40 projecting upwardly from which is a standard 41 through which extends the pipe 34, the housing 33 being positioned within the standard 41. Mounted on the upper end of the standard is the horizontally disposed plate 42 having the upwardly projecting bracket forming arms 43 and 44 which serve to support the reel construction shown in Fig. 2. This permits of a portable arrangement and also the use of the device

where its suspension from the ceiling or the like would be impracticable.

While I have illustrated and described the preferred forms of construction of my invention, I do not wish to limit myself to the precise details of structure shown, but desire to avail myself of such variations and modifications as may come within the scope of the appended claim.

Having thus described my invention, what I claim as new and desire to secure by Letters Patent is:

A device of the class described, comprising: a pair of spaced brackets; a tube; a cylindrical, reel-forming, solid drum fixedly mounted on said tube and having a radially directed passage extended inwardly from its periphery and communicating with an axially directed passage positioned outwardly of the periphery of said tube and opening through an end face of said drum; a block fixedly mounted in one end of said tube; a trunnion projecting outwardly from said block and journaled in one of said brackets, said block having a radially directed passage extending inwardly from its periphery and communicating with a central passage extending through said trunnion; a conduit for connecting the passages in said block with the passages in said drum; a nipple secured in the outer end of the radially directed passage in said drum; a pipe secured in the outer end of the passage directed through said trunnion; leak proof swivel means for connecting said pipe to a water delivery pipe; a block rotatable in the opposite end of said tube; a trunnion on said block fixed in the other of said brackets; and a spring loosely positioned in said tube and attached at one end to one of said blocks and at its opposite end to the other of said blocks.

In testimony whereof I have signed the foregoing specification.

ABRAHAM LUDWIG.
